RADIATION BARRIER APPARATUS

Glen R. Harting, Rockford, Ill., assignor to Borg-Warner Corporation, Chicago, Ill., a corporation of Illinois
Filed Dec. 31, 1962, Ser. No. 248,345
1 Claim. (Cl. 52—404)

This invention relates to protecting devices against the effects of radio-active bombs, radio-active materials, and the like, and has for its primary object to provide an improved construction which is adaptable to presently-installed, residential or commercial buildings while affording a combined protection against harmful rays as well as heat and high temperatures.

Another object of this invention is to provide an economical and simple device which may be installed by non-skilled homeowners to achieve a reliable protective barrier against the harmful effects of injurious rays such as those emitted from an atomic bomb blast.

Still another object of this invention is to provide a device which is adapted to cooperate with present standard home construction and which may be unitized in multiples thereof according to the area and size of the space to be protected, the device being particularly light in weight and, in one aspect of this invention, requires no additional room space than that which is ordinarily designed for occupation.

Yet another object of this invention is to provide a radiation barrier device adapted to cooperate with currently installed home constructions which not only affords the advantages of radiation protection, but which is also adaptable to wall or ceiling installations and which provides domestic advantages such as sound retardation between occupied spaces and a thermal barrier for normal domestic heating purposes, etc.

Other and more particular objects, uses, and advantages of this invention will become apparent upon the reading of the following specification taken in connection with the accompanying drawings which form a part thereof, where in:

FIGURE 1 is a sectional elevational view of a portion of conventional home construction and illustrates the manner in which this invention may be used;

FIGURE 2 is an enlarged sectional view of the barrier construction of this invention and is taken substantially along lines 2—2 of FIGURE 1; and

FIGURE 3 is an enlarged fragmentary sectional view like that of FIGURE 2 and illustrates another embodiment of this invention.

Referring now to the drawings, more in detail by characters of reference, the numeral 10 indicates a portion of a subterranean wall which has a conventional home monolithic concrete basement wall, having one side exposed to the outside terrain 11 and an inside surface which is exposed to living space therein. In most home constructions, wooden joists span the distance between the top portions of the concrete construction and are normally spaced apart 16 inches between centers of each. Spanning the floor joists may be a conventional construction consisting of a sub-floor 12 having wood strips laid thereacross in tight adjacent fitting relationship and a finished wood flooring 13 laid directly thereover.

It is contemplated by this invention to employ the spaces existing between the floor joists and, in another embodiment thereof, also the layer of space directly beneath the joists for purposes of providing a radiation barrier construction. Since the mass of the radiation barrier contemplated herein is a heavy, dense material, it is recommended that additional joists for structural members 14 be placed in the same fashion as the existing joist so as to separate the space between the joists into two separate

2

chambers, the structural elements then having a spacing of approximately 8 inches on centers. Metallic sheet metal strips 15 are placed along the longitudinal bottom margin of the sides of each joist and secured thereto by fasteners 16 such as common carpentry nails. Each mounting strip has an inner lip 17 which is bent out slightly from the side of each joist but retains a direction disposed toward the sub-floor 12.

Retainer means 18 consists of sheet metal and is formed to span the distance between the mounting brackets of adjacent joists as well as provide additional chamber space enclosed therein along with the chamber space between joists; each retainer is formed with a mounting flange 19 having a portion 19a disposed adjacent the side of the strip 15 and has a return-bent lip 19b adapted to cooperate with portion 19a to envelop the lip 17 of the mounting strips. The side portion 20 of each retainer is adapted to conform to the contour of the bottom of each joist and extend downwardly from a central plane of the joist to mate with a bottom portion 21 of the retainer spaced below the plane of the bottom of the joist approximately 4 inches.

In new house constructions, radiation barrier materials, such as sand 22, may be dropped into the chambers between the joists before the sub-floor is laid; or, in existing constructions, sand may be inserted or introduced into the chamber between joists by means such as a sand sling operation through slots 24 (as shown in FIGURE 1) in a manner so that the sand fills all the voids of the chambers therebetween.

The bottom portion 21 of each of the retainer means are adapted to lie in a plane so as to automatically form a metallic finished ceiling for the living space underneath. The metallic nature of the retainer means provides for a slight amount of resiliency so that shock waves experienced during an explosion will not cause cracks or fissures in the barrier construction.

Rays emitted from an atomic blast will normally be entering the housing construction at an angle with respect to a horizontal plane thereof. Thus, the wood joist, forming a relatively good ray protection in itself, will not necessarily form a free passage in comparison to the sand material for rays to reach the occupied space. Rays will at some portion of their travel have to pass through the sand material because of their angular path. Other barrier materials may be used within the chamber such as pulverized oxides that are denser than sand and may therefore exhibit a higher increment in radiation protection. However, for economical home construction, the density of sand and the joists together form adequate radiation protection barriers for normal purposes. The granular nature of the material, however, aids in the manner of introduction of the material to the chambers in existing constructions when an entrance consists of a slot only.

FIGURE 3 illustrates still another embodiment of this invention and similar reference characters are used for parts similar to those in FIGURE 1, prefixed by "2." In this embodiment, the supporting strips 219 are formed in pairs and each comprises a U-shaped mounting bracket adapted to fit about the full end of each joist and having outwardly turned lips at the ends of each U-shaped portion. Such variation permits the installation of several more mounting strips with the same manual operation and provides for quicker installation. The retainer means 218 are adapted to have their bottom portions 221 lie in a plane common with the bottom of each joist so that the actual barrier chamber will have an approximate depth equal to that of the depth of each joist. Thus, the barrier construction can be wholly contained within the space normally unused between the joist and therefore will not

interrupt the construction or remodeling of space below such joist construction.

What is claimed is:

A radiation barrier construction for a domestic dwelling having regularly spaced elongated wooden floor joists and a wooden subfloor placed thereover, each joist having a vertical dimension greater than the lateral spacing between said joists, said construction comprising: sheet metal mounting strips secured to and along the elongated lower margins of each joist and arranged for one mounting strip on each joist to be oppositely facing one mounting strip on an adjacent joist, each mounting strip having a first elongated part extending along the said margin of each joist and secured thereto flush against the element and a second part comprised of an outwardly biased elongated lip, said lip being adapted to flex in a direction toward said supporting joist; retainer means comprising an elongated sheet metal channel adapted to extend between oppositely facing mounting strips to define a closed chamber in cooperation with the adjacent joist and said subfloor, said retainer means depending from the said joists and adapted to abut adjacent retainer means below the joists, each retainer means having elongated flanges adapted to hang upon said mounting strips by the provision of elongated flanges having return

bent lips which are adapted to flex in a direction away from the supporting joist during insertion of said retainer means upon said mounting strips; and radiation barrier material having a density at least as dense as sand, said material being disposed within said chambers filling the voids thereof whereby said radiation barrier material and wooden joists provide a continuous radiation barrier layer to protect occupants beneath.
